UNITED STATES PATENT OFFICE.

THOMAS C. McDERMOTT, OF UTICA, NEW YORK.

BRICK AND WALL CONSTRUCTION.

1,330,884.

Specification of Letters Patent. Patented Feb. 17, 1920.

Application filed May 4, 1917. Serial No. 166,287.

To all whom it may concern:

Be it known that I, THOMAS C. McDERMOTT, of Utica, in the county of Oneida and State of New York, have invented certain new and useful Improvements in Bricks and Wall Construction; and I do hereby declare that the following is a full, clear, and exact description thereof, which will enable others skilled in the art to which it appertains to make and use the same, reference being had to the accompanying drawings, and to the reference-numerals marked thereon, which form part of this application.

My present invention relates to hollow bricks or building blocks and to wall constructions made therefrom and also to a double brick adapted to be burned in its double form and then readily split apart into two separate complete hollow bricks of the kind first mentioned.

One purpose of my invention is to provide a hollow brick or building block of improved construction and of such shape and form as to make an improved brick and one that may be readily and very advantageously formed into wall constructions either by itself or in combination with solid bricks or other forms of building blocks or building material.

30 A further purpose is to provide a brick of such form and a wall structure of such construction that a better wall is easily secured and a better air circulation is secured longitudinally of the wall and where needed vertically also.

40 A still further purpose is to provide a new combination of parts in a wall construction, whereby practically a double wall is secured with proper air spaces between said walls and also proper air spaces are provided through each of the separate halves of the double wall and at the same time the two halves of the wall are tied together by the body portion of each brick.

45 A still further purpose is to provide an improved form of double brick adapted to be readily constructed in its double form and adapted to be burned in its double form without deformation and then readily split apart into two separate bricks.

50 A further purpose is to provide a double brick of such construction that an advantageous arrangement of the parts is secured both as regards the building quality of the completed halves or bricks proper and also

as to the burning qualities of the brick, whereby the parts reinforce each other so that the brick may be burned in a practical way without deformation of the bricks or the parts thereof. A further purpose of my 60 invention is to provide a brick or building block of such form and a wall construction of such character that the air spaces in or between the hollow bricks may be readily continued around a corner or angle without 65 using special members but simply by arranging some of the bricks in a different manner.

Further purposes and advantages of my invention will appear from the specification and claims herein.

70 Figure 1 is an isometric projection of a single hollow brick or building block embodying my invention.

Fig. 2 is an isometric projection of a double brick embodying my invention and 75 illustrating the form in which the bricks are made and burned to be thereafter split apart to form two complete hollow bricks.

Fig. 3 is an isometric projection of a partially completed corner of a wall construction 80 embodying my invention and utilizing hollow bricks or building blocks of this invention.

Fig. 4 is a vertical section on line 4-4 of Fig. 3.

85 Referring to the drawings in a more particular description, it will be seen that Fig. 1 shows an isometric projection of a single brick embodying my invention. This brick has a body portion 7 extending the width 90 and length of the entire brick and having one of its sides or surfaces 8 form one of the faces of the brick. This surface 8 is preferably substantially flat as shown. From the other surface 9 of said body portion 7 there 95 project four integral longitudinally arranged flanges 10, 11, 11 and 10 spaced apart about as shown and with the outer flanges 10 and 10 upon the opposite edges of the body portion or flush therewith and adapted to 100 have their outer surfaces form flat sides or edges 12 for the brick as a whole.

105 From each outer flange 10 to the inner flange 11 next adjacent thereto extends a bridge portion 13 spaced from the inner surface 9 of the body portion 7, whereby a longitudinally extending open-ended but closed-topped air chamber 14 is provided upon each side of the brick and extending longitudinally thereof. No bridge portion 13 or 110

other member connects the oppositely disposed inner flanges 11, 11 after they leave the body portion 7. In this way an open-ended and also open-topped channel 15 is 5 provided extending lengthwise of the brick and midway of its width. It will now be seen that I have provided a brick which in appearance and in fact might be said to be two hollow bricks of ordinary construction 10 bound together in spaced relation by a connecting member which is the middle part 7^a of the body portion 7, said connecting member being flush with one face of the brick.

The brick will preferably be of such size 15 and proportions that each of its said hollow halves will indeed approach more or less closely to the size and proportions of an ordinary solid brick and the complete brick may occupy in a wall the space usually filled by two or more ordinary solid bricks.

This form of brick it will be seen may be readily placed in a wall to form a wall of 20 two parts, each part being of substantially the thickness of a solid brick wall where the bricks are laid lengthwise but being hollow as where ordinary hollow bricks are used, but having the two halves of the wall positively tied together by the connecting portion 7^a of each brick, said connecting portion 25 of course being that part of the body portion 7 which extends from one inner flange 11 to the other inner flange 11. When a straight wall is thus built from laying my bricks lengthwise it will be seen that 30 three parallel air chambers 14, 15 and 14 are provided in the wall and that in a straight wall the said air chambers of one brick connect directly with similar air chambers in the two adjoining bricks in the same course 35 and so on as far as needed or as far as such 40 regular straight construction is carried.

Notwithstanding that an ordinary brick of my construction is two or three times the size of an ordinary brick, my brick may be 45 handled or laid by the brick layer as conveniently and rapidly as an ordinary single brick. This arises partly from the fact that the brick is hollow and of such construction that it weighs not much more than an ordinary 50 solid brick and partly from the fact that the two hollow halves composed of a flange 10, a flange 11 and a bridge portion 13 and a part of the body portion 7 may be 55 grasped flatwise between the brick-layer's thumb and fingers in the same manner as ordinary sized bricks are grasped. It will be noted that the open-topped channel 15 extends far enough down into the brick or 60 between the two halves of the brick to afford ample space for the fingers or thumb to pass down therein and that thus the brick may be handled as a whole by the brick-layer grasping either of its halves.

Preferably a shallow mortar-receiving recess 65 will be provided in the top of each

half of a complete brick as a brick is viewed in Fig. 1. This recess is provided partly for the purpose of providing a mortar-receiving recess, whereby in both plain and irregular brick laying the wall may be tied 70 more securely together and also partly to provide a brick of such construction that when two bricks are formed in the shape of a double brick as shown in Fig. 2 and burned in that shape the double brick may 75 be readily split apart to form two complete bricks. I have shown these recesses 16 as being equal in width with the side channels 14, which may be done by having the bridge portions 13 slightly spaced from the extreme 80 outer edges 17 and 18 of the flanges 10 and 11 respectively. It will be understood, however, that the shallow recesses 16 may be wider or narrower and that I am not limited to the exact construction shown in the draw- 85 ings.

In order to insure that hollow bricks of the special form already described and with a single relatively thin connecting bridge portion 7^a between its two halves may be 90 constructed and burned without breakage, warping or other deformation from the incident handling or burning and shrinkage, I form and burn two complete bricks of the form shown in Fig. 1 as a double brick 95 shown in Fig. 2. In other words, the complete bricks are formed and burned as two bricks having their body portions 7 away from each other and with their flanges 10 and 11 extending toward each other and in 100 fact connected to each other respectively at all four flanges of each brick as plainly shown in Fig. 2. It will now be seen that a shallow recess 16 of one brick faces and connects with a shallow recess 16 in the 105 oppositely formed brick to form one relatively thin chamber extending lengthwise of the brick around each side of each double brick. This chamber formed by two of said recesses 16 is of such thickness that the opposing surfaces of the two bricks of each double brick will not unite after being once formed nor during the burning of the brick. The width of the recesses 16 is also such 110 that the parts connecting one brick to its opposite brick may be readily broken in a straight line when the bricks have been burned and are to be split. This splitting in a straight line and especially without damaging the edge of the completed brick 115 is further facilitated by scoring or cutting part way into the material along the plane in which the double brick is to be split. This is preferably done by scoring or cutting into the material of the double brick 120 when it is being formed along the lines 19 on the outer edges of the double brick and along the lines 20 between the chambers 15 of each brick of the double brick. The 125 scoring or cutting at line 19 is along the 130

upper edges of a completed single brick, thus insuring a neat and true corner and edge at each side of the brick. The scoring 19 extends part way between the facing edges 17 and 17 of opposing bricks, while the scoring 20 extends part way between the opposing edges 18 of the inner flanges 11 of the bricks of a double brick. This scoring in combination with the shallow recesses 16 insures an easy and straight cleavage between the two bricks of a double brick after it has been burned for the reason that there is considerably less material to be broken along the lines of said scoring lines 19 and 20 than at any other part of the flanges 10 or 11 or elsewhere in the brick. It will be understood, however, that the scoring at lines 19 and 20 is shown considerably exaggerated both as to width and thickness of the space left in the unburned brick. A very thin scoring sufficiently separates the material of the two bricks so that it will not re-unite at that plane when the brick is being burned. A shallow scoring also is enough to sufficiently weaken the material so as to insure its ready splitting upon the lines 19 and 20. The said scoring in fact is so thin as to make the cut in the burned brick practically unnoticeable to the eye and leaves no perceptible shoulder upon the upper edges of the flanges 10 or 11. Hence such scoring or any line therefrom does not appear in the drawings of the completed brick such as Figs. 1, 3 and 4.

Furthermore, the shallow recesses 16 beyond each bridge portion 13 perform another function, in that after the brick is formed and before it is burned the two pairs of said recesses 16 form a pair of shallow chambers extending lengthwise of the double brick between opposite bridge portions 13. In this way a thorough air circulation is obtained through the double brick, allowing it to dry much more readily and evenly than would otherwise be the case, thereby preventing distortion or twisting of the brick.

Figs. 3 and 4 show an example of a wall and angle construction embodying my invention. It will be understood, however, that my form of wall construction is not limited to the precise form shown nor to the precise arrangement of bricks arranged therein. The drawings do, however, show plainly one good form of wall construction embodying my invention and clearly show the advantage of this construction and of my improved brick when used in an angle of a wall.

Fig. 3 shows a small portion of two walls brought together and forming an angle in the wall. The straight walls are shown as constructed entirely of my form of brick laid lengthwise with the wall one brick wide and in the main especially in the straight

upper edges of a completed single brick, thus insuring a neat and true corner and edge at each side of the brick. The scoring 19 extends part way between the facing edges 17 and 17 of opposing bricks, while the scoring 20 extends part way between the opposing edges 18 of the inner flanges 11 of the bricks of a double brick. This scoring in combination with the shallow recesses 16 insures an easy and straight cleavage between the two bricks of a double brick after it has been burned for the reason that there is considerably less material to be broken along the lines of said scoring lines 19 and 20 than at any other part of the flanges 10 or 11 or elsewhere in the brick. It will be understood, however, that the scoring at lines 19 and 20 is shown considerably exaggerated both as to width and thickness of the space left in the unburned brick. A very thin scoring sufficiently separates the material of the two bricks so that it will not re-unite at that plane when the brick is being burned. A shallow scoring also is enough to sufficiently weaken the material so as to insure its ready splitting upon the lines 19 and 20. The said scoring in fact is so thin as to make the cut in the burned brick practically unnoticeable to the eye and leaves no perceptible shoulder upon the upper edges of the flanges 10 or 11. Hence such scoring or any line therefrom does not appear in the drawings of the completed brick such as Figs. 1, 3 and 4.

Furthermore, the shallow recesses 16 beyond each bridge portion 13 perform another function, in that after the brick is formed and before it is burned the two pairs of said recesses 16 form a pair of shallow chambers extending lengthwise of the double brick between opposite bridge portions 13. In this way a thorough air circulation is obtained through the double brick, allowing it to dry much more readily and evenly than would otherwise be the case, thereby preventing distortion or twisting of the brick.

When desired the central air chamber of one course of bricks may be connected to the air chamber in an adjacent course of bricks by reversing the usual arrangement of one or more bricks in a course. This is illustrated by the brick 25 in Fig. 4, which I have shown as being laid bottom side up. The central air chamber of this brick will therefore still maintain its connection with the central air chamber in the bricks at each end thereof and though facing down will connect with the bricks therebelow, which have their central air chamber opening upward. It will thus be seen that whenever it is desired the wall may have its central air chambers connected for as many courses as desired.

The corner or angle construction shown in

4

Figs. 3 and 4 is constructed by having the last or nearest brick 27 in the lowest or first course from the left-hand wall extend sufficiently through the corner portion of 5 the wall so that a common solid brick 26 will bring that course of bricks out flush with the outer line of the right-hand wall. The nearest brick 28 from the right-hand wall will be brought up flush with the right- 10 hand end of the solid brick 26 and with the inner side of the brick 27 from the left-hand course, which extends part way through the corner. The single solid brick 26 will therefore close all the air chambers 15 in the near end of the left-hand brick 27. The ends of the air chambers of the right-hand brick 28 will be closed by coming next to the end of the solid brick 26 and to the inner flat and imperforate side of the left- 20 hand brick 27. In the next course a single solid brick 29 will be placed at the corner but extending lengthwise relative to the left-hand wall. The brick 30 from the right-hand wall will extend up to solid brick 29 and overlap the solid brick 26 and the 25 regular brick 27 of my construction of the course below. The brick 30 will be laid upside down. The first brick 31 in the left-hand wall will have its near end come up 30 flush with the farther end of solid brick 29 and the rear flat side of brick 30. The central air space of the right-hand wall will now connect with the central air space from the left-hand wall. This will be apparent 35 from an inspection of the arrangement of the bricks in the third and fourth courses of Fig. 3 as well as from the sectional showing in Fig. 4. The third and fourth courses are similar in arrangement to the first and 40 second courses respectively already described in detail. In Fig. 3, however, the single solid bricks are omitted from the third and fourth courses in order to more clearly show the construction of the corner 45 and especially the connection of the air chambers.

It will now be seen that the brick 30 of the fourth course being upside down has its central air chamber 15 opening 50 downward and that this downward opening of chamber 15 overlaps the upward opening 15 of brick 27, which is laid right side up. This will not be prevented even when the wall is completed by placing the solid 55 brick 26 at the corner of the third course and the solid brick 29 at the corner of the fourth course. The solid brick 26 will close all the end openings of brick 27 and the end opening of one side chamber and part of the end 60 opening of the central chamber of brick 28. Similarly the solid brick 29 will be placed at the corner of the fourth course and will close all the end openings of the air chambers in brick 30 and the end opening 65 of the outside chamber 14 of brick 31 as well as part of the end opening of brick 31. The proportion of the bricks embodying my invention, however, is such relative to each other and to the solid brick being used that the near end of brick 30 will overlap the upwardly opening central air chamber 15 of the near end of brick 27. In this way a sufficient passage is left to connect the air chamber 15 of brick 30 of the fourth course to the central air chamber 15 of brick 27 of the third course. 70

An examination of Fig. 4 will show that the air chamber 15 of brick 30 communicates with the central air chamber 15 of the bricks next along in the fourth course of 80 the right-hand wall, and furthermore that this would be so whether the bricks back from brick 30 were laid right side up or upside down.

Furthermore, it will be seen from Fig. 4 85 that the downwardly opening central air chamber 15 of brick 30 overlaps the upwardly opening central air chamber 15 of brick 28 of the third course. As the central opening in brick 28 communicates with the 90 central opening of the bricks farther along in this course, it will thus be seen that the central air chambers of the third and fourth courses of the right-hand wall and the third course of the left-hand wall are all in communication, insuring an ample circulation of air through the corner of the wall. It will be obvious furthermore that by simply turning the brick 31 of the left-hand fourth course upside down the central air chambers 95 of the third and fourth courses of said left-hand wall will be in communication with themselves and also with the central air chambers of the third and fourth courses through the corner and out along the right-hand wall. It will thus be seen that I have provided a brick and a construction for walls that provides an ample passage of air through the corners or angles of walls to overcome all the disadvantages that arise 100 where a solid corner has to be made either with solid brick or with so called hollow brick, which require so many solid bricks at the corner as to prevent an air circulation through or about the corner. In other 1 words, I have provided a form of hollow brick wherein not only a practical but a very excellent corner is made by utilizing only one small solid or special brick on each course at a corner. 1

The hollow bricks of my invention are also well adapted to bear the strain of having building timbers rest directly thereupon without special construction for the points where such timbers are to rest. In Fig. 3 1 I have shown the end of a timber 32 as resting upon the inner half of the upper side of a brick laid in what I have termed right side up position. The half of the brick receiving such timber being tubular 1

in form is well able to support the load. The shallow mortar-receiving recess on the top of said brick will of course be filled with mortar to more widely distribute the load, but the fact that the bridge portion 13 connects the flanges 17 and 18 so close to their top edges prevents any undue strain upon said flanges or upon the brick. The fact that two halves of each brick are connected by the central body portion 7^a further strengthens the wall for receiving the weight of timbers. On the other hand, where desired a very large and entirely flat timber-supporting surface may be readily obtained by placing a brick at that point upside down, resulting in the large flat surface 8 of brick being uppermost, affording plenty of supporting space and even more widely distributing the weight.

20 From what has already been said with regard to the shape and advantages of my brick and the advantages of my invention in brick wall construction it will be seen that my invention is not limited to the 25 specific form of wall here shown, but may be used in various forms of walls.

It will be obvious that various modifications in the form of my invention may be made without departing from the claims 30 hereinafter set forth.

What I claim as new and desire to secure by Letters Patent is:

1. In a wall structure of bricks each having a body portion extending the width of the brick with one plane surface forming one face of the brick and each having four longitudinally arranged spaced flanges of substantially equal height extending from the other surface of the body portion and 35 each having bridge portions connecting each outer flange to the flange next within whereby three open-ended chambers are formed of which the outer ones are closed by said bridges at the other face of the 40 brick and the middle chamber is open at said second face of the brick and whereby 45

a wide mortar receiving surface is provided adjacent each side of the brick and the brick may be laid with either face to adjoining bricks without changing the courses, the 50 combination of bricks having their said central air chambers facing upward and bricks having their central chambers facing downward and registering with the central air chambers below whereby the central air 55 chambers of adjacent courses are connected.

2. In an angle wall structure of solid bricks and bricks each having a body portion extending the width of the brick with one plane surface forming one face of the 60 brick and each having four longitudinally arranged spaced flanges of substantially equal height extending from the other surface of the body portion and each having bridge portions connecting each outer flange 65 to the flange next within whereby three open-ended chambers are formed of which the outer ones are closed by said bridges at the other face of the brick and the middle chamber is open at said second face of the 70 brick and whereby a wide mortar-receiving surface is provided adjacent each side of the brick and the brick may be laid with either face to adjoining bricks without changing the courses, the combination of 75 chambered bricks extending part way into the angle and having their said central air chamber facing upward, chambered bricks on the next course up extending part way into the angle and having their central air 80 chambers facing downward and registering with the central air chambers below whereby the said central chambers of adjacent courses are connected about the angle and a solid brick in each course in the apex of 85 the angle adapted to close the ends of the open-ended air chambers of the chambered bricks.

In witness whereof I have affixed my signature, this 14th day of April, 1917.

THOMAS C. McDERMOTT.
